CLAIM

The ornamental design for a cleaning device as shown and described.

DESCRIPTION

FIG. 1 is a top front perspective view of a cleaning device showing a first embodiment of the claimed design;

FIG. 2 is a rear bottom perspective view of the cleaning device showing the first embodiment of the claimed design;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a top front view of the cleaning device showing a second embodiment of the claimed design;

FIG. 10 is a rear bottom view of the cleaning device showing the second embodiment of the claimed design;

FIG. 11 is a front view thereof;

FIG. 12 is a rear view thereof;

FIG. 13 is a left view thereof;

FIG. 14 is a right view thereof;

FIG. 15 is a top view thereof;

FIG. 16 is a bottom view thereof;

FIG. 17 is a top front view of the cleaning device showing a third embodiment of the claimed design;

FIG. 18 is a rear bottom view of the cleaning device showing the third embodiment of the claimed design;

FIG. 19 is a front view thereof;

FIG. 20 is a rear view thereof;

FIG. 21 is a left view thereof;

FIG. 22 is a right view thereof;

FIG. 23 is a top view thereof; and,

FIG. 24 is a bottom view thereof.

(Continued)

All of the broken lines illustrate unclaimed features that do not form a part of any of the embodiments, and the broken lines form no part of the claimed design.
